UNITED STATES PATENT OFFICE.

BUDDE SCHIFFENHAUS, OF NEWARK, NEW JERSEY.

MACHINE FOR FORMING PAPER HAT RINGS.

Application filed December 6, 1924. Serial No. 754,385.

To all whom it may concern:

Be it known that I, BUDDE SCHIFFENHAUS, a citizen of the United States, and a resident of Newark, in the county of Essex and State of New Jersey, have invented a new and Improved Machine for Forming Paper Hat Rings, of which the following is a full, clear, and exact description.

This invention relates to machines for forming paper rings used in supporting hats when packed in a box for shipment and has for an object to provide an improved construction wherein the rings may be made quickly and always of the same size.

Another object of the invention is to provide a machine for making paper rings for supporting hats wherein the rings are formed with beads or rolled edges which act both as a stiffening structure and as means for preventing injury to the hat when the ring is in use.

A still further object in view is to provide a machine for forming paper rings for supporting hats wherein the machine wraps a covering strip of paper over either edge or both edges of the ring.

In the accompanying drawings—

Figure 1 is a sectional view through Figure 2, on line 1—1.

Figure 2 is a top plan view of a machine for forming paper rings, the same disclosing an embodiment of the invention.

Figure 3 is a fragmentary view partly in section showing a pair of combined feeding and forming rollers.

Figure 4 is a fragmentary view partly in section showing a second pair of forming and feeding rollers together with a cam structure for assisting in turning over certain parts.

Figure 5 is a view partly in section showing the finishing forming rollers.

Figure 6 is a fragmentary view and outline of the contacting portions of the measuring and cutting rollers.

Figure 7 is a fragmentary perspective view showing one edge of the finished ring.

Figure 8 is a perspective view of the structure shown in Figure 7 looking at the same from another angle and illustrating how the coiled wire belt is removed from the bead.

Figure 9 is a plan view of a finished ring blank.

Figure 10 is a perspective view of a complete ring ready for use.

Figure 11 is a sectional view through Figure 10, approximately on line 11—11, the same being on an enlarged scale.

Figure 12 is a detail fragmentary perspective view illustrating how the cam shown in Figure 4 functions.

Referring to the accompanying drawings by numerals, 1 indicates a framework of any desired kind which is formed with suitable bearings, braces and the like for accommodating the various moving parts including the particular new features of the invention. As indicated in Figure 1, there is provided shafts 2 and 3, shaft 2 having gear wheels 4 rigidly secured thereto while the shaft 3 is provided with gear wheels 5 meshing with gear wheels 4. In addition, the shaft 3 is provided with a driving pulley 3' which may be driven from any suitable source of power. The shaft 3 is provided with a pair of feed rollers 6, said rollers being identical so that the description of one will apply to both. The shaft 2 is also provided with a pair of cutting rollers 7, said rollers being of identical construction so that the description of one will apply to both.

As indicated in Figure 2, the various rollers 6 and 7 are spaced apart for engaging the strip of paper 8 near the respective edges. In fact, strips of tissue paper or other suitable wrapping paper 9 and 10 are provided and fed from a suitable supply, said strips engaging the respective rollers 6 and suitable other feeding and forming rollers hereinafter fully described whereby when the finished ring is provided rolled edges will be presented and said edges will be covered by the strips 9 and 10. The two top rollers 6 co-act with the respective pairs of feeding and forming rollers 11, 12 and 13 so as to turn over the edges of the strip 8 and form the bead 14.

As indicated in Figure 3, the rollers 6 are provided with grooves 15 which co-act with the grooves 16 on the rollers 11. A belt 17 round in cross section is provided for each of the rollers 11, said belts being preferably spiral wire belts as shown particularly in Figure 8. These belts force part of the strip 8 and the strips 9 and 10 into the grooves 15. As the strip 8 and the strips 9 and 10 leave the rollers 11, the edges of all these strips engage the respective folding cams 18 and 19 (Figure 4), said cams causing the strip 8 with the strips 9 and 10 to be turned up and then folded over so that the

rollers 12 will complete the bead or rolled edge 14. However, part of the respective belts 17 are in the bead or folded edge 14 and must be removed. In order to accomplish this removal, pulleys 20 and 21 are provided, said pulleys being supported by suitable bolts or pins 22 and 23 adjustably positioned in the respective slots 24 and 25. The pulleys 20 and 21 are offset toward a central line between the respective rollers 13 as indicated in Figure 2 whereby as the strip 8 and the belts 17 move forwardly, the belts will be gradually moved out of the bead or turned over edge 14 as indicated in Figure 8. This will leave the bead somewhat open and the rollers 7 will then act to close the bead.

It will be noted that the lower runs of the respective belts 17 are inclined toward a central line of the machine so that the lower runs of the belts will be pulled out of the folded edge 14. The strips 8, 9 and 10 passing through the machine will be acted on as just described and will finally pass between the respective rollers 6 and 7. In passing from between the rollers 6 and 7 as indicated in Figures 1 and 6, a knife or cutter 27 (Figure 6) cuts the respective slits 28 and 29 for forming the tongues 30 and 31, after which, the knife 32 cuts the strips 8, 9 and 10 so that a single blank 33 is discharged. As the machine continues to operate, one or more slitting knives 34 function to provide the various slits 35 in the end of the blank 33 opposite the tongues 30 and 31. In forming the slits 35 the paper is fed further through the machine and the operation of forming the tongues 30 and 31 is repeated. After a blank has been formed, as for instance, blank 33, the same is manually bent into a circle and the tongues 30 and 31 inserted through one set of the slits 35 as indicated in Figure 10 whereupon the ends of the block are locked together and a complete ring is presented ready for use. It will be noted that the complete ring as shown in Figure 10 is provided with beads or rounded edges 36 and 37 and that by positioning the tongues 30 and 31 in different sets of slits 35, the size of the ring may be varied. It will, of course, be evident that one bead or edge could be provided for the finished ring instead of two. Also, it will be evident that the strips 9 and 10 could be eliminated and the beads or turned over edges provided. However, it is preferable to use the strips 9 and 10 because the paper 8 is heavy paper of some kind and often cracks when being turned over at the edges. This will present a rough surface which is undesirable and, therefore, the covering or wrapping of the tissue paper strips 9 and 10 around the edges functions to positively present a smooth edge which will not injure the hats when the rings are in use. In use,

the rings are to be placed over the crowns of hats, particularly men's hats when they are stored in boxes or even placed on shelves, whereby the crown will be supported above the support of the rim.

When the machine operates, the same may be caused to function at high speed or low speed and the various strips 8, 9 and 10 fed into the machine from various sides. As these strips pass over the various rollers heretofore described, the edges will be formed and finally separated blanks 33 will be successively discharged from the machine. In forming the two rollers 6, preferably each is formed with a cut-out or notch 38 which is substantially filled by a wedge-shaped plate 39 carrying block 40 of hard wood or soft metal, said block being adapted to act as an anvil against which the cutter 32 presses without cutting a finished blank from the strip 8. The rollers 7 are likewise formed with a notch 41 which is substantially filled by a wedge-shaped member 42 carrying the various knives or dies 27, 32 and 34. These members may be held in place by screws or any suitable means. The wedge members 39 and 42 also may be held in place by set screws or other suitable means. The shafts 2 and 3 are mounted in suitable bearings, the bearing of shaft 2 being preferably fixed in any desired manner while the bearing of shaft 3 is slidingly mounted in suitable slots in the frame whereby different size rollers 6 and 7 may be used. Also the various rollers 6 and 7 are slidably mounted on the respective shafts 2 and 3 and held in any desired adjusted position by suitable set screws. The various rollers 11, 12 and 13 are also slidably mounted on their supporting shafts and locked in different positions by suitable set screws. The slots 24 and 25 permit a proper adjustment of the pulleys 20 and 21 whereby the belt 17 may properly function. It will be noted that the lateral adjustment of the rollers 6 and 7 and also the rollers 11, 12 and 13 is to permit the formation of rings of different heights or widths, according to the various demands on the manufacturer. When a given pair of rollers 6 and 7 are used, as for instance, the size shown in Figure 1, the length of the blank will always remain the same but the width may be varied as desired. If a different length is desired, a different size set of rollers 6 and 7 should be used.

What I claim is:—

1. In a machine for forming paper rings for hat supports, a pair of rollers, a plurality of cutting members on one of said rollers for cutting a strip of paper passed around the other roller, said cutting means acting to cut the paper into sections and to cut each section so as to provide a slit at one end, and a tongue at the opposite end,

and means co-acting with one of said rollers for turning over the edge of the paper to form a bead thereon before it is discharged from the machine.

- 5 2. A machine for forming paper rings for hat supports, comprising a supporting roller structure having a pair of grooves, said roller structure being adapted to receive a continuous strip of paper, a cam for 10 turning over the opposite edges of said strip of paper for forming a hollow bead, a plurality of roller structures co-acting with the first mentioned roller structure acting on the turned over edges for completing the bead, 15 and means for severing said strip of paper into lengths.
3. A machine of the character described, comprising a pair of feed rollers, each of said feed rollers having a groove in the periphery, said feed rollers being adapted to receive a strip of paper which will extend from one roller to the other and overlap said grooves for an appreciable distance, a plurality of forming rollers for each of the 20 feed rollers, each of said forming rollers being provided with a groove arranged in line with the grooves in the feed rollers, a belt round in cross section passing over said forming rollers whereby the belt passing over the first set of forming rollers will push the paper into the grooves in the feed rollers and will hold the paper in said grooves until the paper moves away from the belt, means 25 for turning the edge of said paper in a preliminary manner until the same is partially folded over said belt, certain of said forming rollers acting on said turned over paper for completing the turning action so as to present a hollow bead on each edge of said 30 paper, and means co-acting with said feed rollers for cutting said paper into lengths.
- 40 4. A machine of the character described,

comprising a pair of feed rollers, each roller having a peripheral groove, a plurality of forming rollers co-acting with the feed rollers, each of said forming rollers having a groove in line with the grooves of the feed rollers, a pair of cams, said cams being arranged so that the one will operate in connection with each of the feed rollers for 45 turning over a strip of paper passed over the feed rollers, said cams acting to turn the edge of said paper, a pair of belts round in cross section passing over all of said forming rollers, a pulley wheel for each of said 50 belts offset toward each other from a straight line with said forming rollers, and means co-acting with said feed rollers for cutting the paper fed over the feed rollers into lengths.

5. In a machine of the character described, means for receiving a strip of paper and turning the edge over for forming a hollow bead, said means including a pair of belts round in cross section, a cam acting on 55 each edge of the paper strips for pressing the folded edges over said belts, a pulley for each belt spaced from said rollers and also offset towards each other from a straight line from said pulleys whereby as the paper 60 passes from certain of said forming rollers the belts will move out of said bead, and means for cutting said paper into lengths.

6. In a machine of the character described, means for receiving a strip of paper and forming beads on each edge, means for cutting the paper into lengths after said beads have been formed, and means for forming slits at one end of said severed lengths and tongues at the opposite end 70 whereby the tongues may be inserted into said slits for holding the lengths into circular formation.

BUDDE SCHIFFENHAUS.
